Primary Examiner—Ted Shooman*Assistant Examiner*—C. Tuttle*Attorney, Agent, or Firm*—Nawrocki, Rooney & Sivertson,
P.A.[57] **CLAIM**

The ornamental design for a safety razor cartridge, as shown and described.

DESCRIPTION

FIG. 1 is a top plan view of a safety razor cartridge showing my new design;

FIG. 2 is a left side elevational view thereof;

FIG. 3 is a right side elevational view thereof;

FIG. 4 is a front elevational view thereof;

FIG. 5 is a rear elevational view thereof;

FIG. 6 is a perspective view thereof; and,

FIG. 7 is a front perspective view thereof with a holder attached thereto.

The broken line showing of the razor handle is for illustrative purposes only and forms no part of the claimed design.
